SUPPORTING HORSE

Benjamin Poll, Holland, Mich.

Application December 6, 1939, Serial No. 307,748

2 Claims. (Cl. 304—5)

The present invention relates to supporting horses commonly called saw-bucks and more particularly to supporting horses of the knock-down type which may be assembled or knocked down as desired.

The primary objects of the instant invention are to provide an improved metal coupling for coupling the supporting legs and the cross bar of a supporting horse in rigid assembly; to provide such a coupling which is economical in manufacture; to provide such a coupling which is compact in form; and, to provide such a coupling which is efficient in its intended use.

An illustrative embodiment of the invention is shown in the accompanying drawing, wherein:

Figure 1 is a side elevational view of a supporting horse assembled for use by means of a pair of my improved metal couplings;

Figure 2 is an end elevational view of the same; and

Figure 3 is an enlarged perspective view of a metal coupling per se.

Referring to this drawing wherein like parts of the supporting horse and its couplings are designated by the same numerals in the several views, my improved metal coupling for a supporting horse comprises a cross-sectionally U-shaped body member 10 having a horizontal medial portion 11 and upstanding leg portions 12 with aligned notches 13 therein formed by striking flanges 14 horizontally outwardly from the said leg portions 12 at the bottom of the notches 13. These aligned notches 13 form a socket for the reception of an end of the cross bar 15 of the supporting horse.

A pair of U-shaped yokes 16 are preferably formed separately from the body member 10 and are each thereafter welded to the body member on opposite sides thereof, the leg portions 17 of each yoke 16 being welded as indicated at 18 to the leg portions 12 respectively of the body member 10.

The medial portion 19 of each U-shaped yoke 16 is inclined downwardly-outwardly with respect to the body member 10, and each yoke 16, with the medial portion 11 of the body member 10, forms a socket extending upwardly-inwardly to intersect with the horizontal socket in which the cross bar 15 is disposed.

The upper end portions of supporting legs 20 adapted to support the horse 15 are received in the inclined sockets formed between the yokes 16 and the medial portion 11 of the body member 10 and the upper extremities of said supporting legs 20 are in abutting engagement with the cross bar 15.

It will thus be seen that the cross bar 15 is

tightly wedged between the pairs of supporting legs 20 at the opposite ends of the supporting horse and that downward force applied to the cross bar 15 serves to wedge the parts together in even more rigid assembly.

It will be further seen that the metal coupling herein shown and described may be economically made of stamped and bent sheet metal and that no waste of sheet metal occurs in such manufacture since the flanges 14 serve as supporting ledges for the cross bar 15 thereby eliminating any sharp edges at the bottom of notches 13 which sharp edges would cut into the cross bar 15.

While but one specific embodiment of the invention has been herein shown and described, it will be understood that certain details of the construction shown may be altered or omitted without departing from the spirit of the invention as the same is defined by the following claims.

20 I claim:

1. A supporting horse coupling comprising a cross-sectionally U-shaped member whose upstanding leg portions are each provided with a transverse notch each in alignment with the other for the reception of a cross bar, and a pair of U-shaped yokes secured to said body member at opposite sides thereof respectively, each U-shaped yoke having its leg portions secured to the leg portions respectively of the body member and each having its medial portion inclined downwardly-outwardly with respect to the body member, and each yoke being adapted to embrace the upper end portion of a supporting leg between said yoke and the medial portion of the U-shaped body member for maintaining the upper extremity of said supporting leg in abutting engagement with said cross bar.

2. A supporting horse coupling comprising a cross-sectionally U-shaped body member whose upstanding leg portions are provided with aligned notches for the reception of a cross bar, flanges on said leg portions extending horizontally outwardly from the bottoms of said notches, and a pair of U-shaped yokes secured to said body member at opposite sides thereof respectively, each U-shaped yoke having its leg portions secured to the leg portions respectively of the body member and each having its medial portion inclined downwardly-outwardly with respect to the body member, and each yoke being adapted to embrace the upper end portion of a supporting leg for maintaining the upper extremity of said supporting leg in abutting engagement with said cross bar.

BENJAMIN POLL.
